(57) **CLAIM**

The ornamental design for jewelry with modified yin yang symbol, as shown and described.

DESCRIPTION

FIG. 1 is a front perspective view of jewelry with modified yin yang symbol showing my new design;

FIG. 2 is a front perspective view of a second embodiment of jewelry with modified yin yang symbol showing my new design;

FIG. 3 is a front perspective view of a third embodiment of jewelry with modified yin yang symbol showing my new design;

FIG. 4 is a front perspective view of a fourth embodiment of jewelry with modified yin yang symbol showing my new design;

FIG. 5 is a front perspective view of a fifth embodiment of jewelry with modified yin yang symbol showing my new design; and,

FIG. 6 is a front perspective view of a sixth embodiment of jewelry with modified yin yang symbol showing my new design.

The jewelry with modified yin yang symbol is flat, with no raised or recessed features.

The characteristic feature of the design resides in the three shadings of black, white and gray.
